UNITED STATES PATENT OFFICE

LOUISE HENRIETTA BOCH, OF NEW YORK, N. Y.

WINDOW-SHADE MOUNTING.

1,338,168.

Specification of Letters Patent. Patented Apr. 27, 1920.

Application filed October 10, 1919. Serial No. 329,782.

To all whom it may concern:

Be it known that I, LOUISE H. BOCH, a citizen of the United States, residing at New York, in the county of New York and 5 State of New York, have invented certain new and useful Improvements in Window-Shade Mountings, of which the following is a specification.

The invention has for its primary object 10 the mounting of a window shade and hangings in such manner as to enable the same to be swung to a position at an angle to the plane of the window to shield a portion of the room interior while admitting light to 15 other portions, and to securely hold them in such angular position, while not interfering in the slightest degree with the raising and lowering of the shade and adjustment of the curtains, draperies, etc.

20 It is also the aim of this invention to accomplish such object in a thoroughly mechanical manner, conducing to efficiency of operation, and at a minimum of cost of installation, with an avoidance of complicated structural elements liable to become deranged through carelessness or ignorance.

The invention has its especial field of usefulness in connection with windows opening into courts opposite other windows, as 30 in the case of inside rooms of hotels and the like, where it has heretofore been necessary to insure privacy for dressing by the lowering of the shade and dependence upon artificial light, also as a means of gaining access to the window for cleaning purposes, and as a protection of curtains and draperies against soiling by rain or being drawn out of an open window by a draft.

It has been proposed heretofore to accomplish some of these objects in a somewhat similar manner and I make no claim broadly to the angular adjustment of shades, but in all such prior attempts the mounting has been so unmechanical and the operating of 45 the shade so complicated as to be of little practical value, the manner of operation not being at once obvious to a guest introduced thereto for the first time and consequently unfamiliar therewith. In such circumstances the utility of the device has not been 50 recognized or attempts at using the same has resulted in its disarrangement and the destruction of its usefulness.

A characteristic feature of my invention,

therefore, is its simplicity, its ease of manipulation, and the immediately obvious manner of its intended operation and use.

In order that the invention may be readily understood a detailed description of a preferred embodiment of the same follows, 60 predicated upon an illustrative drawing, in which drawing—

Figure 1 is an interior elevation showing the invention as applied to a window;

Fig. 2 is a top plan view;

Fig. 3 is a fragmentary horizontal section on the line 3—3 of Fig. 1; and

Fig. 4 is a detail view of the window mount as used for a plurality of rollers.

In the drawings the glazed window opening is indicated at 11 and the window frame or casing at 12. Hinged to the window frame at 13 is a window mount comprising a horizontally disposed bar 14, and upon this bar are affixed the shade brackets 15 for 70 the carrying of the shade roller 16 in the usual manner.

A vertically disposed rod 17 is journaled at 18 on the window frame at one side of the opening, the upper end of the rod 17 being 80 cranked at 19 and attached at 20 inwardly from the hinge 13 to the case mount 14.

An operating arm 21 carrying the handle 22 is connected to the lower end of the rod 17, preferably by articulation, and extends 85 angularly therefrom. This arm 21 is arranged to traverse the segment plate 23 attached to the window frame either at the side or at the bottom and is provided with spaced teeth or notches 24, with which 90 notches the arm 21 is adapted to engage and be held in adjusted position.

For purposes of stability, a brace rod 25 is rigidly connected to the rod 17 at 26 and extends obliquely to a point of adjustment 95 at 27 with the shade mount.

It will be readily understood from the foregoing description, taken in connection with the drawing, that by grasping the handle 22 and swinging the arm 21 angularly the shade mount and the shade roller and shade 16 will likewise be swung angularly about the hinge 13, and the dropping of the arm 21 into one of the notches 24 of the segment plate 23 will securely lock the 100 rod 17 and the shade at any desired adjusted angle to the window opening. Another locking device is illustrated in the thumb set

screw 27 which may be employed in conjunction with or independently of the arm 21 and notches 24. This may be done while the shade is entirely lowered and the angular adjustment of the shade will in no manner interfere with the raising and lowering of the shade upon its roller. Desired portions of the room may then be shielded from observation, without materially reducing the illumination of the room from the window. There is nothing to get out of order and no familiarity with the operating mechanism is required to enable one to operate the device to secure the desired results.

A characteristic feature of the present invention is the utilization of a plate or bar adapted for the mounting thereon of ordinary types of shade or curtain brackets, by reason of which the purchaser of the mounting can use thereon the usual shade, curtains or draperies already in hand and is not required to purchase specially designed fittings therefor.

Moreover, as illustrated in Fig. 4, both the shade roller 16 and curtain or drapery rollers or rods 16^a can be applied to the same swinging mount by the attachment thereto of additional brackets 15^a, thus enabling all to be swung together to a position at any desired angle to the window, shielding the room interior while admitting light and air, giving access to the window for washing, preventing soiling by rain when an open window is desired, precluding the draperies from streaming out of the window, and the like.

I claim:

1. In a device of the character described, a shade mount adapted to be hinged at one end to the window frame above and at one side of the window opening, shade brackets at the two ends of the mount, a shade roller adapted to be mounted in the brackets, a rod journaled in a vertical position on the window frame and having its upper end attached to the shade mount at the hinged end, an operating arm extending angularly from the lower end of the rod, and means for locking the arm to hold the rod and shade mount in adjusted position.

2. In a device of the character described, a shade mount adapted to be hinged at one end to the window frame above and at one side of the window opening, shade brackets at the two ends of the mount, a shade roller adapted to be mounted in the brackets, a rod journaled in a vertical position on the window frame and having its upper end attached to the shade mount at the hinged end, an operating arm extending angularly from the lower end of the rod, and means for locking the arm to hold the rod and shade mount in adjusted position, and a brace rod extending obliquely from the vertical rod

to a point of attachment to the shade mount intermediate its length.

3. In a device of the character described, a shade mount adapted to be hinged at one end to the window frame above and at one side of the window opening, shade brackets at the two ends of the mount, a shade roller adapted to be mounted in the brackets, a rod journaled in a vertical position on the window frame and having its upper end deflected and attached to the shade mount at a point spaced inwardly from the hinge, an operating arm extending angularly from the lower end of the rod, means affixed to the window frame and arranged to be traversed by the arm and to hold the same in adjusted position.

4. In a device of the character described, a shade mount adapted to be hinged at one end to the window frame above and at one side of the window opening, shade brackets at the two ends of the mount, a shade roller adapted to be mounted in the brackets, a rod journaled in a vertical position on the window frame and having its upper end deflected and attached to the shade mount at a point spaced inwardly from the hinge, an operating arm extending angularly from the lower end of the rod, means affixed to the window frame and arranged to be traversed by the arm and to hold the same in adjusted position, and a brace rod extending obliquely from the vertical rod to a point of attachment to the shade mount intermediate its length.

5. In a device of the character described, a shade mount adapted to be hinged at one end to the window frame above and at one side of the window opening, shade brackets at the two ends of the mount, a shade roller adapted to be mounted in the brackets, a rod journaled in a vertical position on the window frame and having its upper end cranked and attached to the shade mount at a point spaced inwardly from the hinge, an operating arm articulated to and extending angularly from the lower end of the rod, a notched plate affixed to the frame and arranged to be traversed by the arm and to hold the same in adjusted position.

6. In a device of the character described, a shade mount adapted to be hinged at one end to the window frame above and at one side of the window opening, shade brackets at the two ends of the mount, a shade roller adapted to be mounted in the brackets, a rod journaled in a vertical position on the window frame and having its upper end cranked and attached to the shade mount at a point spaced inwardly from the hinge, an operating arm articulated to and extending angularly from the lower end of the rod, a notched plate affixed to the frame and arranged to be traversed by the arm and to hold the same in adjusted position,

and a brace rod extending obliquely from the vertical rod to a point of attachment to the shade mount intermediate its length.

7. In a device of the character described, 5 a horizontally disposed shade mount comprising a bar adapted to be hinged at one end to the window frame above and at one side of the window opening, shade brackets at the two ends of the mount, a shade roller 10 adapted to be mounted in the brackets, a rod journaled in a vertical position on the window frame and having its upper end cranked and attached to the shade mount at a point spaced inwardly from the hinge, an 15 operating arm articulated to and extending angularly from the lower end of the rod, a notched segment plate affixed to the frame and arranged to be traversed by the arm and to hold the same in adjusted position.
- 20 8. In a device of the character described, a horizontally disposed shade mount comprising a bar adapted to be hinged at one end to the window frame above and at one side of the window opening, shade brackets 25 at the two ends of the mount, a shade roller adapted to be mounted in the brackets, a rod journaled in a vertical position on the window frame and having its upper end cranked and attached to the shade mount at 30 a point spaced inwardly from the hinge, an operating arm articulated to and extending angularly from the lower end of the rod, a notched segment plate affixed to the frame and arranged to be traversed by the arm 35 and to hold the same in adjusted position, and a brace rod extending obliquely from

the vertical rod to a point of attachment to the shade mount intermediate its length.

9. In a device of the character described, a shade mount comprising a wooden bar 40 adapted to be hinged at one end to the window frame above and at one side of the window opening and to serve for the attachment thereto of a plurality of sets of window shade and drapery brackets, a rod 45 journaled in a vertical position at the side of the window opening and having its upper end attached to the hinged end of the mount, and means for axially turning the rod and for securing the rod and mount in 50 adjusted position.

10. In a device of the character described, a shade mount comprising a wooden bar adapted to be hinged at one end to the window frame above and at one side of the 55 window opening and to serve for the attachment thereto of a plurality of sets of window shade and drapery brackets, a rod journaled in a vertical position at the side of the window opening and having its upper end deflected and attached to the hinged end of the mount at a point inwardly of the hinge, and means for axially turning the rod and for securing the rod and mount 60 in adjusted position.

In testimony whereof I have hereunto signed my name in the presence of two subscribing witnesses.

LOUISE HENRIETTA BOCH.
